No. 36,897.

Patented May 3, 1904.

UNITED STATES PATENT OFFICE.

ALEXANDER J. BALISH, OF NEW HAVEN, CONNECTICUT.

DESIGN FOR A MEDALLION OR SIMILAR ARTICLE.

SPECIFICATION forming part of Design No. 36,897, dated May 3, 1904.

Application filed February 13, 1904. Serial No. 193,480. Term of patent 3½ years.

To all whom it may concern:

Be it known that I, ALEXANDER J. BALISH, a citizen of the United States, residing at New Haven, in the county of New Haven and State of Connecticut, have invented a new, original, and ornamental Design for a Medallion or Similar Article, of which the following is a specification, reference being had therein to the accompanying drawing, forming part

thereof, in which the figure represents a plan view of the medallion or similar article.

What I claim as my invention is—

The ornamental design for a medallion or similar article, as shown.

ALEXANDER J. BALISH.
